[57] **CLAIM**

The ornamental design for a projection adapter for a conventional television receiver, substantially as shown and described.

DESCRIPTION

FIG. 1 is a front, top and left side perspective view of a projection adapter for a conventional television receiver showing my new design;

FIG. 2 is a rear, top and left side perspective view;

FIG. 3 is a rear elevational view;

FIG. 4 is a right side elevational view;

FIG. 5 is a bottom plan view;

FIG. 6 is an exploded view like FIG. 2; and

FIG. 7 is a view similar to FIG. 2 of a modified form of a projection adapter for a conventional television receiver showing my new design, wherein the base is deeper and the sides of the base are wider.

FIG. 6

FIG. 7
